UNITED STATES PATENT OFFICE

167,153

ADHESIVE TAPE DISPENSER OR THE LIKE

Theodore H. Krueger, Stratford, Conn., assignor to Better Packages, Inc., a corporation of New York

Application August 20, 1951, Serial No. 16,381

Term of patent 14 years

(Cl. D74—1)

To all whom it may concern:

Be it known that I, Theodore H. Krueger, a citizen of the United States, residing in Stratford, county of Fairfield, State of Connecticut, have invented a new, original, and ornamental Design for Adhesive Tape Dispenser or the like, of which the following is a specification, reference being had to the accompanying drawings, forming part thereof, in which

I claim:

The ornamental design for an adhesive tape dispenser or the like, substantially as shown.

THEODORE H. KRUEGER.
